UNITED STATES PATENT OFFICE.

GEORGE BEACOCK, OF BROCKVILLE, ONTARIO, CANADA, ASSIGNOR OF TWO-THIRDS TO CHARLES H. MCCREADY, OF SAME PLACE, AND T. JAMES CLAXTON, OF MONTREAL, CANADA.

ARTIFICIAL LEG.

SPECIFICATION forming part of Letters Patent No. 433,226, dated July 29, 1890.

Application filed February 11, 1890. Serial No. 339,963. (No model.)

To all whom it may concern:

Be it known that I, GEORGE BEACOCK, a subject of the Queen of Great Britain, residing at Brockville, in the Province of Ontario, 5 Dominion of Canada, have invented certain new and useful Improvements in Artificial Limbs, of which the following is a specification, reference being had therein to the accompanying drawings.

10 This invention has relation to artificial limbs, and more particularly to that class which are made of rawhide, and the objects and advantages of the invention will be herein-after described, and the novel features 15 thereof will be particularly pointed out in the claims.

Referring to the drawings, Figure 1 is a side elevation, partly in section, of an artificial limb constructed in accordance with my invention. Fig. 2 is a rear elevation of the knee-joint. Fig. 3 is a rear elevation and partial section of a modified form of the ankle-joint. Fig. 4 is a section on the line xx of Fig. 1, and Fig. 5 is a detached view of the pivot-bolt 25 and its wrench.

Like letters refer to like parts in all the figures.

A represents the socket or thigh portion, and it is provided at its upper edge with a 30 rubber pipe, tube, or cord A', having canvas or other material A² lapped around the same, with its free edges inserted in a slit A³, extending around the upper edge of the thigh, and the whole is then covered with rubber, 35 leather, cloth, or other suitable facing A⁴, the free edges of which are cemented or otherwise secured to the interior or exterior faces of the thigh. This construction produces a cushion or marginal finish of the upper end 40 of the thigh and prevents abrasion or irritation of the stump of the wearer.

B represents one of a pair of arms, which are members of the hinge-connection of the thigh with the leg-piece of the limb. The 45 remaining member B' of the hinge comprises two arms connected by a semicircular band B². These members are inserted within the hollow rawhide thigh and leg pieces and secured thereto by rivets, as clearly shown.

C represents a bolt forming the pivot-bearing of the hinge-joint. This bolt consists of two sections C', having a threaded dowel C² centrally and longitudinally arranged therein, while each end of the bolt is provided with a tapering recess C³ and a flange C⁴, which extends completely around and projects from the body of the bolt. Wrenches D are provided, the operative portions of which are simply cylindrical and tapered, so that by forcing them into the recesses C⁴ the frictional 55 contact of the wrench with the walls of the recess is rendered sufficient to turn the sections C' in opposite directions, and thus to separate the same and permit of the removal of the pivot from the joint. 65

E is a pivot-bridge, consisting of one or, if desired, more plies of rawhide extending diametrically from front to rear, across and within the hollow leg portion of the limb at the knee-joint. The lower end of the thigh 70 portion is a hollow sphere, and is slotted or recessed, as at F^x, to bestride the bridge E, and it is transversely bored for the reception of the bolt C. By this construction the entire weight at the joint is supported by the 75 bridge and the bolt, while the bridge strengthens the knee-joint against displacement by torsional strain. In other words, the joint is kept in alignment by the bridge, while the upper edge of the bridge serves as a stop to 80 the backward movement of the joint by coming in contact with the bottom of the recess F^x. The stoppage of the forward movement of the joint is effected by the contact of the upper edge of the leg portion with the rear 85 surface of the thigh portion along the line, where the same merges into the spherical termination thereof.

F is a tendon or thong of rubber secured at one end to a hook F' fastened upon the 90 interior of the thigh portion. The tendon is extended into the recess F^x of the knee-joint and passes from thence through a box F² formed through the bridge and from thence to a point below and within the leg portion, 95 as at F³. The passage of the tendon or thong through the box F² is an advantage in that it brings the pull of the spring in such a line

as to give it the greatest effort in drawing the leg and foot portions forward in the act of walking. It can readily be seen that this pulling action would be less if the tendon 5 were extended freely and directly from the point F' to the point F², as it would pass in close proximity to the center of pivotal motion. In Fig. 4 the box F² is formed by dividing the plies of the bridge and forming 10 them, as shown, and securing each ply to the leg portion at opposite sides of the central vertical line. When made of a single piece of material, the boxing may be made by boring through the bridge.

15 At the lower end of the leg portion G of the limb there is inserted a hollow extension G', which is slotted at its upper edge, so as to form tongues G², which are riveted or otherwise secured to the interior of the leg. The 20 lower end G³ of the extension G' is somewhat cylindrical and is transversely apertured for the passage of the pivot-bolt C, which also passes through the sides of the foot portion H. Said extension G³ is provided 25 with an inwardly-projecting hollow horn G⁴, which is adapted to strike against the inner surface of the bottom of the foot. A spring H' projects from the horn and bears on the inner surface of the top of the foot, and has a 30 tendency to elevate the toe thereof.

The upper edges of the foot portion at the ankle are cut in at each side of the foot on inclined lines H², converging toward the center of the bolt C, but terminating at a distance therefrom, where the edge of each opening is on a curved line concentric with said bolt. The extension G' has shoulders G⁵, which may be concave in outline, as shown 35 in Fig. 1, or convex, as shown in Fig. 3, and 40 conform to the curvature of the lines H², on which the sides of the foot are formed. Said extension also has a shoulder G⁶ at the rear, against which the upper edge of the back of the foot abuts. The shell or outer portion of 45 the leg extends below the upper edges of the foot portion, so that said edges at each side of the ankle are arranged between the leg and its interior extension G', thereby preventing lateral displacement of the parts where 50 they bear upon each other. This gives great strength to the ankle-joint. It will of course be understood that the same effect would be produced by a reversal of the parts—that is, if the shoulders G⁵ were convex, as shown in 55 Fig. 3, and the lines H² correspondingly formed.

By the construction of the ankle-joint just described it will be seen that substantially the entire weight and pressure is removed 60 from the bolt so that in both joints of the limb creaking at the pivot is prevented. This advantage is contributed to from the fact that the bolt is of such a construction that it can

turn in its bearings, while its dowel, being preferably made of brass and the body of the 65 bolt of steel or any other contrasting metal, oxidation or rusting of the sections, so as to prevent an easy separation of the same, is avoided.

What I claim is—

70 1. In an artificial limb, a cushion for the socket, comprising a rubber filling, a flexible covering having its free edges inserted in the material of the socket, and a facing having its free edges secured to the surfaces of the 75 socket, substantially as specified.

2. A joint for an artificial limb, comprising a spherical termination of a thigh having a slot or recess therein, a bridge arranged in the slot or recess and secured within the leg 80 portion, and a thong or tendon secured to the thigh and leg and passing through the bridge, substantially as specified.

3. A knee-joint for an artificial limb, comprising a perforated bridge, a slotted or recessed thigh, a thong connecting the leg and thigh and passing through the bridge, and a bolt passing through the leg, the bridge, and the thigh, substantially as specified.

85 4. A bolt for artificial limbs formed in sections and having a screw-threaded dowel of metal for connecting the sections, substantially as specified.

90 5. A bolt for artificial limbs, constructed in sections, each having a flange at its outer end 95 and recessed for the reception of a section rotating tool, substantially as specified.

6. In an artificial limb, a bridge having a box for a tendon made of plies of material separated to form the box, substantially as 100 specified.

7. An ankle-joint for artificial limbs, comprising an extension having lateral concave shoulders, in combination with a hollow foot portion having convex side edges, substantially 105 as specified.

8. In an artificial limb, a leg portion terminating in an extension having concave lateral shoulders and a projecting horn, in combination with a foot portion having convex 110 bearing-edges and a spring for lifting the toe of the foot, substantially as specified.

9. In an artificial limb, the combination of a thigh having a slotted extension, a leg having a bridge adapted to the slot of the thigh, 115 a pivot-bolt passing through the leg, the thigh, and bridge, a leg-extension having concave lateral bearing-shoulders, and a foot portion having convex bearing-edges, substantially as specified.

120 In testimony whereof I affix my signature in presence of two witnesses.

GEORGE BEACOCK.
